MINERAL JIG

Leslie E. Tuthill, Seattle, Wash., assignor to L. E. Tuthill, Inc., Seattle, Wash.

Application December 18, 1940, Serial No. 370,571

4 Claims. (Cl. 209—455)

My invention relates to improvements in a mineral jig of the type used in dressing ore to separate heavy materials such as relatively large size mineral particles from lighter materials such as small particles of mineral or gangue by agitating and stratifying such materials in the presence of water or other fluids.

It is well known that the art of mineral recovery requires careful, accurate treatment of mineral bearing materials in order that the maximum recovery can be made in the ore milling operation. The place of the mineral jig in the circuits and methods employed in recovering valuable materials is readily recognized by experts in this field. The basic principles of a mineral jig, however, require refinement and improvement to permit their use more widely to treat complex ores and treat larger quantities of material with a given machine operating power output.

Jigs are ordinarily employed in mill circuits of both the closed and open type and are often used between an ore crusher and the classifier where the materials being treated are sorted as to size. The primary purpose of a mineral jig is to effect an initial recovery of mineral values in the circuit which need not then be further handled through other stages and machines of recovery. An important use of the jig is in recovering gold particles from the fluid discharge of the ore crusher. Such a discharge includes gold particles of all sizes, sulphides, quartz particles and other metallic or non-metallic substances of value or not. The accumulation or mass of material is conveyed by water. These solids contained in the fluid, having various rates of settling because of their differing specific gravities, present difficult separation problems to the mill operator. However, the employment of these differentials is essential in jig treating ore in order to accomplish the desired separation.

In mills employing both the open or closed grinding circuit, ore is ground or crushed and passed to a jig through suitable conduit means and in the presence of water. This crushed ore-bearing fluid is introduced to the jig by means of a launder or trough and is caused to flow over the jig bed where it is activated to produce stratification of the solids according to size and specific gravity.

The jig bed is usually mounted in a frame having a lower screen which may be divided on its upper face into compartments. On the upper face of the screen and in the compartments, if they be used, is placed a quantity of bedding,

usually metal shot of a size and weight which may be varied to determine the size and nature of particles that are to be passed downwardly and be recovered in the jig as a mineral concentrate. The volume of downward flow is regulated by varying the depth of the jig bed.

In operation, the jig bed, having fluid borne particles flowing thereover, is pulsated or raised periodically to effect stratification and to momentarily open or make permeable the jig bed to permit ore particles having greater specific gravity than the material forming the jig bed to pass therethrough. As the periodic pulsation of the jig bed ceases and the individual members of the jig bed close together through the effect of gravity, particles lighter than the jig bed are thus trapped above it and are carried away by the lateral flow of fluid across the jig bed.

20 The particles which pass down through or permeate the bedding of the jig are collected in a lower tank or hutch. The material thus concentrated is substantially pure value suitable to be immediately reduced to a marketable product in the form of ingots or even as metallic granular concentrate.

It is well known that jigs are useful to recover free gold which need not be treated in the full milling circuit and is easily recovered. In addition, jigs are useful to simplify the flotation operation, improve the operation of the filters and thickeners, eliminate amalgamation plates as well as for countless other reasons.

35 The jigs commonly in use heretofore have employed the principle of fluid agitation to activate the jig bed. In accordance with these principles a heavy periodic flow of water is applied to the under side of the jig bed. This raises the jig shot bed and separates the bedding elements to permit the material being concentrated to settle or permeate through the bed. During a subsequent quiescent period the bedding returns to rest in its support.

45 Such periodic flow of water has been produced by tilting the jig frame to and fro to cause the enclosed fluid to surge from end to end under the jig bed. Another form of periodic agitation is that resulting from the use of diaphragm pistons in a wall of the jig hutch, the diaphragm being agitated from without by various types of mechanisms. Walking beams have been employed to operate the diaphragm as also have various other types of linkage arrangements. The result of these arrangements is to impart a surge or agitation which tends to rise rapidly,

attain a peak, and then fall rapidly without any sustained peak. This is undesirable because of the extremely short period afforded for concentrates to pass thru the jig bed.

A prolonged suspension of the jig bed will permit a greater downward flow of materials sought to be concentrated and thus is more efficient concentration possible. It has been an important object of this invention to provide a jig having a cycle of operation in which the suspension period of the jig bed is prolonged to keep the shot bed open or permeable as long as possible.

Another object of my invention has been the incorporation of my novel prolonged suspension period principle into a jig without adding to the complexity of construction or operation of the jig.

A further object of the invention has been the employment of a tilting beam or double bell crank actuator mechanism having incorporated therewith a novel operating means to produce a new and useful change in the mode of agitation produced.

Still another object of the invention has been to provide means operable by the agitator mechanism for drawing the charge of agitation fluid into the jig container to thereby eliminate exterior pressure means and rotary injection valves on the source of feed to the jig hutch.

Another object of the invention has been the provision in a jig of peak sustaining means operable in conjunction with the pulsator means employed.

Still a further object of my invention has been to provide a riffle trough suspending and agitating mechanism for jigs which is resiliently mounted and positively agitated to aid and enhance particle stratification in the cross flowing fluid being treated in the jig.

Other and more specific objects and advantages of the invention will become apparent during the course of a reading of the following specification and a study of the accompanying drawings in which I present a preferred embodiment of my invention. It will be understood for the purposes of the description of this invention, that while I have described its application to the recovery of gold particles from fluid carrying crushed ore, I do not wish to be limited in the scope of my invention to such installations. The uses of such a device are many and varied and only limited by the ingenuity of designers of ore dressing plants.

In the drawings,

Figure 1 is a side elevation of my mineral jig with portions broken away for convenience of illustration,

Figure 2 is a front elevational view of my jig also with portions broken away for convenience of illustration,

Figure 3 is a plan view of the jig showing associated therewith a feed launder and a tailing or overflow launder,

Figure 4 is a fragmentary sectional view taken on line 4-4 of Figure 3, and illustrating the general arrangement of the jig bed and an agitating baffle employed in the combination,

Figure 5 is a cross-sectional view through the launder as though taken on line 5-5 of Figure 3,

Figure 6 is a fragmentary cross-sectional view taken on line 6-6 of Figure 3.

Figure 7 is a cross-section of the agitator shaft of the baffle taken on line 7-7 of Figure 5,

Figure 8 is a sectional view illustrating the pulsating mechanism as positioned in an initial

stage of an agitation cycle, in which a charge of fluid is drawn into the valved inlet chamber,

Figure 9 is a similar sectional view of a secondary stage in the agitation cycle at which point the valve chamber has been completely filled with a fluid charge,

Figure 10 is a similar view, further disclosing a subsequent stage of the agitation cycle and more it specifically shows the relation of the elements of construction as the valved inlet chamber is being discharged of its contained fluid,

Figure 11 illustrates the final stage of the agitation cycle with the inlet chamber about to be closed and the displacement diaphragm about to start its function,

Figure 13 is a perspective view of a slide block used in connection with the walking beam of my device,

Figure 14 is a perspective view of the bell crank actuator which operates the pulsator mechanism of my mineral jig,

Figure 15 is a perspective view of the diaphragm plate which attaches to the arm of a bell crank in my jig,

Figures 16 and 17 are enlarged fragmentary views of the lever arms, detailing the operation of the slide block and the manner in which the leverage applied to the walking beam, is changed throughout a rotation of the crank.

Figure 18 is a vertical sectional view through a modified form of agitation mechanism in which I have employed the general principles of my invention,

Figure 19 is a vertical sectional view of the same nature as the showing of Figure 18 but illustrating a further modified form of my invention,

Figure 20 is a fragmentary elevational view of an adjustment device employed in a modified form of my invention,

Figure 21 is a vertical sectional view of a modified device according to the principles of my invention and illustrating the mechanism adjusted by the arrangement of Figure 20, and

Figure 22 illustrates a still further form which my invention may take in which a wide range of operating characteristics for the agitation mechanism may be obtained.

Referring to the drawings, the numeral 20 designates a hutch having lower converging sides or walls forming a settling chamber 21 which is substantially of inverted conical shape and which terminates in spout 22 on the lower pointed end. A cleanout valve 23 is fitted in the spout 22 and is provided with a gate 24 which may be locked on occasion.

Rising above the sloping walls of the hutch and disposed atop the settling chamber are side walls 25 and 26 and front and rear walls 27 and 28. The walls 25, 26, 27 and 28 define a rectangular case which is divided medially by a depending plate 29 forming a baffle that divides the enclosed area into an inlet chamber 30 and a pulsation chamber 31.

In the pulsation chamber 31 form a supporting grid 32 which comprises a plurality of structural members arranged in crossed relation in the pulsation chamber and secured to the walls 26 and 33. The grid 32 supports the jig screen 34. As shown in Figures 4 and 5, the jig screen 34 lies upon the upper surfaces of the grid and divides the pulsation chamber into two zones, the

lower adit zone 35 and the upper jig zone 36. On the upper face of the screen I provide shot bed dividers 37 which segregate the jig bed into rectangular areas of substantially smaller size than the total area of the jig bed.

The materials used to form the jig bed, preferably shot or balls of steel 38, is placed on the screen 34, between the shot bed dividers, to a depth of from one to three inches. The jig bed need not be formed of shot as other materials have been found very suitable for the purpose. Therefore I do not wish to be limited by my reference to the use of shot to form the jig bed and it is to be understood that steel shot is described for the purpose of illustration only.

On the upper portion of the walls 28 and 33 I provide vibrator mounts 40 which may be welded, as at 41, to the walls. These mounts are curved and have upper and lower segmental seats 42 and 43 respectively. Between the segmental seats I mount the vibrator balls 44 which have central passages 45. Rime shafts 46 and 47 have their ends disposed in the central passages 45 of opposed pairs of balls in each end of the jig bed zone. By means of the depending arms 48 fitted on the rime shafts 46 and 47, I mount the depending rime walls 49 which lie substantially parallel to the walls 28 and 33. These walls extend downwardly to a point just above the upper surface of the jig bed.

Between walls 49 in spaced apart relation is a series of riffles 50. In Figure 4 it may be seen that the riffles 50 are disposed at a slight angle from the perpendicular and that their lower edges are slightly curved or cupped as at 51. Generally the preferable practice is to employ the riffles with their cupped edges directed rearwardly or with concave faces presented to the material flow across the jig bed as indicated by the arrow in Figure 4.

Members 49 are provided with journal supports 52 which rise upwardly and mount the journals 53 on the rectangular rime box. An agitator shaft 54 is mounted in the journals 53 and is provided with the pulley 55 by which rotative force is applied to the shaft. The pulley 55 may be keyed to shaft 54 or otherwise secured. By means of bolts 56 one side of the shaft 54 has secured thereto a plurality of straps 57 which in toto comprise an overbalance 58 for the shaft. When shaft 54 is caused to rotate this arrangement produces a vibration to the journals 53 which will in turn joggle or vibrate the whole of the rime box and cause it to impart a stratifying movement to the flow of ore-bearing water over the jig bed.

The upper face of the inlet chamber 30 of the hutch is closed by means of the cover plate 59 which has cut therein the openings 61 and 62. A depending inlet housing 63 is secured below the opening 62 and forms the intake chamber 64. A feed duct 65 passes through the wall 27 into the wall of the housing 63.

A stirrup 66 spans the inner terminal of the duct 65, valve disk 67 on the pin 68 is maintained in the closed position by means of the spring 69 between the stirrup 66 and the face of the valve plate.

In the lower wall of the housing 63 I also provide the discharge opening 70 which is spanned by the curved leaf spring 71 that supports the bolt 72 substantially centrally of the opening 70. On the outer face of the housing I provide the valve disk 73 secured to the bolt by means of a nut 74. The normal tendency of the spring 71

is to hold the disk 73 against the outer face of the housing 63 to close the opening 70.

Resilient diaphragms 75 and 76 are secured by bolts 77 over the openings 61 and 62 respectively. Usually the diaphragms are formed of heavy molded rubber to insure long life under adverse conditions. Centrally of each diaphragm I secure the diaphragm plate 78 by means of the series of bolts 79. Each of the plates is provided with a pair of spaced-apart pivot ears 80 that have central pivot holes 81.

Between the openings 61 and 62 and on the cover 60 I mount bearing standards 85 which have mounted therein a pivot pin 86 that is passed through the pivot hole 87 on the double bell crank 88. The bell crank has on either side of the pivot hole, a pair of oscillator arms 89 and 89' having end pivot holes 90. Pins 91 are passed through the holes 81 of the pivot ears on the diaphragm plates and through the holes 90 at the outer ends of the lever arms 89 and 89'.

The bell crank member has also a pair of upstanding arms 92, 93 which form the fork 93 into which is fitted the slide block 94 of Figure 13. Slide block 94 is shown as parted for convenience of assembly.

In journals 96, 96 I mount the drive shaft 97 for rotation and centrally of the drive shaft is the actuator crank 98 supported by means of crank arms 99, 99. The crank 98 is engaged by the halves of the slideable journal slide block 94 and during rotation will impart a tipping motion to the member 88 to raise and lower the lever arms and to in turn impart a plunger-like or piston-like action to the flexible diaphragms.

A drive pulley 101 is keyed to the drive shaft 97 in line with the agitator shaft pulley 55. An endless belt 102 encircles the pulley 55 and 101. Preferably I use a V-belt of rubber composition which will run equally well whether tight or slightly loose.

Material is fed to the jig bed by means of feed launder 104 and tailing material is carried away by means of the overflow launder 105. These launders are placed on either end of the jig bed in the manner indicated in the drawings.

In operation in a typical installation my jig would be placed between the discharge side of a ball mill or other crushing machine and the feed side of a classifier mechanism. It is possible by means of my machine to run directly the unclassified feed material from the crusher mechanism to the jig for treatment according to its mode of operation. Such a feed of material will contain metallic as well as non-metallic material of a great variety of sizes and shapes and all having differing specific gravities.

The material passes into the jig bed zone from the feed launder and flows toward the overflow launder. The first mechanical action imparted to this feed material is that encountered in the agitating or vibrating riffles 50 which are caused to move through the operation of the overbalanced rotary shaft 54. The side plates 49 carrying the riffles oscillate in the rubber mount 44 in a jiggling manner and the motion of the riffles being backward and forward. The incoming feed is thus stirred or spread over the bed of the jig and stratification of this feed material is thereby considerably enhanced. The settling of the gold particles having a great specific gravity onto the bed is aided and assisted and the efficiency of the jig is improved over those devices in which fixed riffles are employed.

A constant supply of water is provided on the

inlet duct 65 and this water, through the operation of the piston means 76 is drawn into the intake chamber 64 during a portion of the cycle of operation of the bell crank mechanism 88. At a later period in the cycle of the jig it is forcefully discharged into the hutch of the jig and imparts pressure to the under side of the shot bed of the jig. This pressure is produced by piston means 75 and applied to the shot bed to cause it to become permeable by raising and the individual elements to separate them and to thus provide openings for the downward passage of the material being concentrated. Gold has a greater specific gravity than the steel balls normally used in the shot bed and the rate of fall of the gold being concentrated will therefore be greater than that of the shot bed. The gold will permeate downwardly through the interstices of the shot bed material and fall into the hutch as indicated in Figure 2 where these particles are accumulated in the lower end of the settling chamber 21 indicated at 107. These concentrates may be drawn off through the clean-out valve 23.

The action of the lever mechanism 88 and of the diaphragms thereby actuated is delineated in the Figures 8, 9, 10 and 11. In Figure 8 the diaphragms over each opening are substantially of equal size and they are also substantially equally distended but, in the showing, the action of the crank 98 is tending to raise the right oscillatable lever arm 89' and to distend further the inlet diaphragm 76. This action maintains the valve member 73 tightly closed while at the same time the valve member 67 is drawn open against the urging of the spring 66 to permit the inward flow of fluid through the duct 65, which operation will culminate with the filling of the chamber 64. Simultaneously, the piston means 75 is being forcefully depressed into the fluid of the hutch and to apply force therein to create a current that will flow to the underside of the permeable jig bed and open it. Of course, in Figure 8 the piston means 75 has only travelled through an initial portion of its stroke and as can be seen in Figure 9 it will be further depressed into the jig hutch.

The chamber 64 is shown completely filled in Figure 9 and when the diaphragm is distended as shown the valve 67 closes when the urging of its spring overcomes the current of the inflowing fluid. Throughout the downward feeding stroke of the piston means 75, the valve 73 will remain closed but the valve 73 will open to permit the flow of fluid into the hutch during retracting or upward stroke of the piston means 75, the initial stages of which stroke are illustrated in Figure 10. The vacuum that would normally create a suck-back on the under side of the diaphragm 75 when it raises is compensated for by the incoming flow of the fluid that was in chamber 64. During the retracting stroke of the piston means 75 no other force is applied to the jig bed elements than gravity.

By eliminating the backward suction from the shot bed I eliminate the undesirable tendency in many jigs of drawing contaminants into the concentrate due to the drawing of light weight particles through the shot bed and into the hutch. The contamination of the concentrate with quantities requires further separation steps that become unnecessary by the use of my jig.

It will be apparent that for each two strokes of the levers of the walking beam only one charge

of fluid is introduced into the hutch, and the shot bed is only raised once.

According to the principles of my invention I produce a current in the hutch, not under pressure of gravity or under the lower pressures obtainable from ordinary water supply sources, but with a positive high pressure imparted through the operation of the piston means. I permit the jig bed to come to rest under the force of gravity by supplying a volume of fluid to the hutch equal to the increase in volume of the hutch produced by retracting the current creating diaphragm. Thus, during this period the jig bed is quiet.

In the showing of Figure 18 wherein I have illustrated the modified structure in which the principles of my invention have been incorporated, the hutch 20 forms the usual inlet chamber 30. The pulsation-chamber wall 33 is to be seen and has attached thereto as described, the launders 104 and 105. The cover plate 110 has cut therein the openings 111 and 112 which are closed by the flexible diaphragms 113 and 114 respectively. The two diaphragms are operated by the conventional walking beam 88 which is pivoted on pin 85 and which is oscillated or tilted by the crank 98. The diaphragms 113 and 114 are of different size with the smaller being disposed over the opening 112 to draw fluid into the inlet chamber 115 through the duct 116. Because of the differential between the effect of the two diaphragms in their up and down travel, a small quantity of fluid will be drawn into the chamber 115 and then when it is drawn into the hutch by the force exerted by the diaphragm 113, it will occupy the void created by the upward movement of that member and will thus relieve the suction to a degree that might otherwise be applied to the underside of the shot bed. This produces a slightly longer interval during which the shot bed is falling freely so that a greater amount of metal particles may pass therethrough.

In Figure 19 the same effect as is produced in the Figure 18 device is obtained by the use of the walking beam 120 which has arms 121 and 122 of different lengths. The effect is to increase the leverage applied on the diaphragm 113 and to decrease the leverage operable upon diaphragm 114. This increases the stroke of the diaphragm 113 while at the same time suction stroke of diaphragm 114 draws less fluid into chamber 115.

In Figures 20 and 21 I teach the use of a variable pivot for the walking beam 125 which is provided with the slot 126 instead of to the conventional pivot hole. A pivot pin 127 has eccentric trunnions 128 which are mounted in the bearing supports 129. A lever 130 is keyed or secured to a trunnion to assist in turning that member and this lever is held in adjusted position by means of the pin 131 which cooperates with the holes in the edge of the quadrant 132. By swinging the lever 130 the crank pin 127 is caused to swing about the axis of the trunnions and to thus shift the pivot point with relation to the centers of the diaphragms. In this way is it possible to shift the action of the walking beam and to increase or decrease the stroke of the piston diaphragms.

The walking beam 135 shown in Figure 22 has the usual central pivotal mounting on pin 136 but the arms of the member are slotted at 137 and 138 and the pins 139 and 140 are fitted thereto. The cover plate 141 is movable laterally across the upper mouth of the hutch 142 and gasket 143 prevents leakage at the point of joinder. Slotted arms 144 are engaged by bolts 145 to hold the plate 141 in adjusted position.

By sliding the plate laterally the relative distances between the pivot pin 136 and the point of attachment of the diaphragms 113 to the arms of the walking beam 135 may be varied to increase and decrease the respective leverages.

By the use of this arrangement various sizes of diaphragms may be employed in the adapting of the jig to the conditions under which it may be required to operate. This device is particularly useful in running pilot or test milling operations upon a type of ore. When an ore mill designer is called upon to specify the type of equipment that should be built into an ore mill he must fit the equipment to the demands of the ore being milled. Various slight alterations will often produce results where failure had existed before. The mechanism of Figure 22 is primarily useful for such testing and experimenting.

I claim:

1. In a mineral jig wherein a pulsating current is employed in a jig hutch to periodically increase and decrease the permeability of a jig bed under a flow of feed material, reciprocal means for imparting an intermittent current to the fluid in said jig hutch, means for intermittently introducing fluid to said jig with force, said introduction of fluid being timed to occur during the retracting stroke of said reciprocal current imparting means, a rotatable shaft having means thereon for reciprocating said reciprocal means, a plurality of vibrator mounts on said hutch adjacent said jig bed, each vibrator mount supporting an upper and a lower segmental seat, a resilient vibrator ball positioned in the seats of each vibrator mount, an open bottom riffle box positioned over the jig bed and having a plurality of trunnions, each trunnion associated with a vibrator ball, an unbalanced shaft associated with said riffle-box to agitate the same, means associating said unbalanced shaft with said rotatable shaft for rotation therewith, and means for rotating said rotatable shaft.

2. In a mineral jig wherein a pulsating current is employed in a jig hutch to periodically increase and decrease the permeability of a jig bed under a flow of feed material, reciprocal means for imparting an intermittent current to the fluid in said jig hutch, means for intermittently introducing fluid to said jig, said introduction of fluid being timed to occur during

the retracting stroke of said reciprocal current imparting means, a rotatable shaft having means thereon for reciprocating said reciprocal means, a plurality of vibrator mounts above said jig bed each including a resilient member, an open-bottom riffle box having a trunnion associated with each resilient member to support the riffle-box above said jig bed, an unbalanced shaft journalled on said riffle-box to agitate the same, means associating said unbalanced shaft with said rotatable shaft for rotation therewith, and means for rotating said rotatable shaft.

3. In a mineral jig wherein a pulsating current is employed in a jig hutch to periodically increase and decrease the permeability of a jig bed under a flow of feed material, reciprocal means for imparting an intermittent current to the fluid in said jig hutch, means for intermittently introducing fluid to said jig, said introduction of fluid being timed to occur during the retracting stroke of said reciprocal current imparting means, a rotatable shaft having means thereon for reciprocating said reciprocal means, a flexible open-bottom riffle box supported in spaced relation above said jig bed, an unbalanced shaft associated with said riffle-box to agitate the same, means associating said unbalanced shaft for rotation therewith with said rotatable shaft, and means for rotating said rotatable shaft.

4. In a mineral jig wherein a pulsating current is employed in a jig hutch to periodically increase and decrease the permeability of a jig bed under a flow of feed material, reciprocal means for imparting an intermittent current to the fluid in said jig hutch, means for intermittently introducing fluid to said jig, said introduction of fluid being timed to occur during the retracting stroke of said reciprocal current imparting means, a rotatable shaft having means thereon for reciprocating said reciprocal means, an open-bottom riffle box flexibly supported in spaced relation above said jig bed, an unbalanced shaft associated with said riffle-box to agitate the same, means associating said unbalanced shaft for rotation therewith with said rotatable shaft, and means for rotating said rotatable shaft.

LESLIE E. TUTHILL.
